UNITED STATES PATENT OFFICE.

HENRY C. WEHRFRITZ, OF JERSEY CITY, NEW JERSEY.

COWL.

Application filed June 15, 1926. Serial No. 116,195.

This invention relates to cowls, an object of the invention being to provide a cowl, in which an outlet tube is provided with an opening in its rear face, which opening is always maintained at the rear by the action of the wind through the cowl.

A further object is to provide a cowl of improved construction that has an improved mounting which insures easy movement of the cowl with the wind.

A further object is to provide an improved cowl which can be manufactured and sold at a reasonably low price and which will most efficiently perform the functions for which it is intended.

With these and other objects in view, the invention consists in certain novel features of construction and combinations and arrangements of parts, which will be more fully hereinafter described and pointed out in the claim.

In the accompanying drawings—

Figure 1 is a perspective view, showing my improved cowl in operative position on a pipe;

Figure 2 is a view in horizontal transverse section on the line 2—2 of Figure 4;

Figure 3 is a view in rear elevation of the cowl;

Figure 4 is a view, in vertical longitudinal section, of the cowl.

1 represents a supporting pipe which is provided with spiders or bars 2 and 3, respectively, in which a vertical rod 4 is secured and constitutes the support of my improved cowl 5. The cowl 5 is in reality a casing, which may be of any suitable material but is preferably of metal and is formed with a closed top 6 and is open both at the front and rear ends.

The cowl is so shaped that the front end is preferably larger than the rear end, as clearly indicated in Figure 2, and while I have illustrated a cowl of general angular form it is obvious that it may be otherwise shaped, the essential, however, being that the front end is larger than the rear end so as to induce a passage of air through the cowl, causing a suction up the pipe 1, as is readily understood.

This cowl 5 has a central tube 7, preferably of slightly larger diameter than the

pipe 1, and the bottom of the cowl is open at the lower end of the tube 7 so as to permit the tube 7 to enclose the upper end of pipe 1.

The tube 7 is formed with spiders 8, having central bearings 9 receiving the rod 4, and a thrust bearing 10 is provided at the top of the cowl to receive the upper end of the rod 4, and these bearings insure free turning movement of the cowl on the rod.

A vane 11 is fixed on top of the cowl so that this vane insures the proper positioning of the cowl in accordance with the direction of the wind.

The tube 7 in its rear face is formed with an opening 12, which opening may be of any desired size but extends around the cowl a distance no greater than one-half of the circumference of the cowl. This opening is positioned at the rear of the tube 7 so that the front wall of said tube acts as a deflector to cause the air to pass around the tube at both sides thereof and induces a suction through the tube 7 and opening 12 regardless of the direction in which the wind is blowing.

It will thus be noted that by reason of the construction above described the vane 11 will insure the cowl being turned to a direction to receive the wind in the larger end of the cowl, and as the wind blows through the cowl around the tube 7, it will induce a suction up the pipe 1 and tube 7 and through the opening 12 in the direction of the wind.

This cowl may, of course, be used either as a smoke outlet, as a ventilator, or in any other place where it is required for flow through the pipe 1 of the cowl and in the direction of the wind. Furthermore, by reason of the construction above described, it is impossible for the wind to blow down the pipe 1, and the mounting insures a free turning movement so that the cowl is sensitive to even the slightest breeze.

Various slight changes and alterations might be made in the general form of the parts described without departing from my invention and hence I do not limit myself to the precise details set forth but consider myself at liberty to make such slight changes and alterations as fairly fall within the spirit and scope of the appended claim.

I claim:

A cowl, comprising a casing open at both ends and larger at one end than at the other, a vertical tube smaller in diameter than the casing and fixedly secured in the casing, said tube having an opening in its wall adjacent the smaller end of the casing, bear-

ings located centrally in the tube above and below the said opening, a thrust bearing in the top of the casing, a pipe receiving the tube thereon, and a vertical rod secured in the pipe and mounted in all three of said bearings.

HENRY C. WEHRFRITZ.
